FIG. 1 is a front elevational view of the shingle having two tabs, with each tab being of a different color and showing the tabs as having beveled edges and a shadow line at the lower edge of the tabs, wherein the broken lines depict environmental structure in the form of unclaimed overlay structure;

FIG. 2 is an end view of the shingle of FIG. 1, with the other end view a mirror image, wherein the broken lines depict environmental structure in the form of unclaimed overlay structure; and,

FIG. 3 is another end view of the shingle of FIG. 1, wherein a different unclaimed environmental structure in the form unclaimed underlay structure from that of FIG. 2 is shown. FIG. 1 is lined for color and the stipple shading shown in FIG. 1 illustrates an area of darker shading.

The broken lines shown in FIGS. 1, 2 and 3 depict environmental structure. The broken lines and the structure they depict form no part of the claimed design.
